UNITED STATES PATENT OFFICE.

WILLIAM E. GIFFORD, OF WORCESTER, AND WILLIS R. SMITH, OF AUBURN, MASSACHUSETTS, ASSIGNORS TO VIKING SPECIALTY COMPANY, A CORPORATION OF MASSACHUSETTS.

SOCKET RATCHET WRENCH.

Application filed October 10, 1921. Serial No. 506,720.

To all whom it may concern:

Be it known that we, WILLIAM E. GIFFORD and WILLIS R. SMITH, citizens of the United States, respectively residing at Worcester and Auburn, both in the county of Worcester and State of Massachusetts, have invented a new and useful Socket Ratchet Wrench, of which the following is a specification.

This invention is an improvement over 10 the construction shown in our application filed Feb. 11, 1921, Serial No. 444,192, and this application is in part a continuation thereof.

The principal objects of this invention are 15 to provide a socket wrench construction with a readily detachable handle so that it can be made up with two sockets projecting in opposite directions and with different handles so as to employ it for screwing up a 20 nut or unscrewing it with a ratchet motion in the most inaccessible places; to provide a simpler and more convenient form of detachable socket so that sockets of different sizes and shape can be kept in stock as a part of 25 the equipment and applied readily without necessitating the employment of a skilled mechanic; and to provide improvements in the means for detachably holding the sockets, and the general arrangement of the device. Although the wrench is designed especially for use in connection with automobiles, it is capable of general use, and is of great utility in the average shop or factory.

Reference is to be had to the accompanying 30 drawings, in which

Fig. 1 is a side view of a wrench constructed in accordance with this invention, with parts in section, to show interior construction;

40 Fig. 2 is a plan of the same; and

Fig. 3 is a similar view of a rod constituting a part of this invention.

In the form illustrated, the invention is 45 shown as comprising a two-headed ratchet wrench. This involves a head 10 of cylindrical shape mounted on each end of a rod 11 which constitutes the handle. The face of each head is constructed in the form of a rack 13 made up of radial ratchet teeth. One 50 rack is left handed and the other right handed. On the ratchet end of each head is a central recess 12 screw threaded at the bottom and having a shoulder at the outer end of the thread.

Screwed into this recess is an axial stud 14, 55 having a slotted head 16 and an enlarged shank engaging the shoulder of the circular recess in the head in which it is located.

As stated above, the wrench is provided with two socket members 20 one located at 60 each end of the handle. Each of these socket members is provided with a circular rack made up of radial teeth fitting the rack 13 on the head itself. Each socket member is provided with a central passage all the 65 way through having at the outer end a socket 21 to fit the nut or bolt head on which it is intended to use it. In practice several sizes of these socket members are provided, each 70 size consisting of a pair adapted to be used for right and left hand respectively. These are intended to be replaced by a pair of another size whenever desired, or they can of course be replaced individually.

At the bottom of the socket 21 is an enlarged recess 22 of cylindrical shape. The continuation of the central passage is designed to receive and guide the head 16, of 75 similar size and shape, on the cylindrical stud 14.

At the bottom the central recess 12 in the socket member 20 has a shoulder on which bears the end of the spring 15. The other end of the spring presses against the under side of the head 16 of the stud 14. This 85 holds the stud 14, and therefore, the socket member 20, in position, but allows it to rotate. At the inner end of the central passage it is reduced to the diameter of the recess 12 to receive the stud 14. This forms a 90 shoulder 17.

In order to permit of a ratchet action when the handle 11 is turned on the axis of the head, the socket members 20 have to be arranged so as to be capable of yielding in an 95 axial direction. For this purpose the spring 15 bears on the shoulder 17 at one end and on the bottom of the head 16 at the other. This spring surrounds the stud 14, and normally 100 forces the stud outwardly in the position shown in Fig. 1, but the spring permits the socket member to move axially relative to the stud, and thus allows the ratchet motion.

In Figs. 1 and 2 we have shown the two heads 10 as connected by a rod 11 which, as 105 stated, constitutes the handle. This rod is shown as hexagonal in the present case and in any case is non-circular. In order to re-

ceive it each head 10 is provided with a passage 23 extending into it from one side at an angle of 90° to the axis of the head and of the same shape as the handle. The handle itself is provided with a transverse recess 24 in which is a spring 25 and a ball 26. The outer end of the passage 24 is contracted so that the ball cannot be dislodged. This ball is pressed with considerable pressure against 10 one of the flat walls of the passage 23 and holds the head and handle together when they are once assembled.

It is to be noted that near each edge of the handle 11 there is a circumferential 15 groove 30 and in this groove there is a circular wire 31 extending substantially all the way around and having its ends located in the groove as well as the rest of the wire. This wire projects from the groove along 20 the flat sides of the handle and constitutes a mere stop for it. It comes against the wall of the head when the handle is inserted.

It is to be noted that the two heads at the opposite ends of the handle are arranged 25 to extend from the handle in opposite directions, although either of them might be turned around 60° or 120° or even 180° with respect to the other on the hexagonal handle. On this account, the device can be used in 30 various places which are otherwise inaccessible.

In the construction shown in Fig. 3 there is a rod 32 having the general characteristics of the handle 11. It has the spring pressed 35 balls 36 like the balls 26 and it has the groove 30 and the wire 31. But in this case only one of these wires is used because this rod is employed as indicated in Fig. 1 for supporting an additional socket member 37 40 on one of the ordinary socket members 20. This is for the purpose of providing a greater range in the utility of the device as will appear readily. The socket member 37 is applied to the socket member 20 by inserting the rod 32 in either one of them 45 up to the wire 31 and then applying it to the other in an obvious manner.

It will be seen that by the arrangements provided the socket members can be applied 50 to the handle at any angle thereto circumferentially but always at right angles to its length, also that the parts can be connected together simply and conveniently and rapidly. These facts render the tool very useful by reason of the ease with which it can 55 be introduced into places that would otherwise be practically inaccessible. The addition of a socket head 37 is also of great importance for the reason that it increases 60 the range of the wrench materially. It will be understood, of course, that this member 37, as well as each of the members 20, while indicating a specific socket head in the drawings, is intended to represent a whole series 65 of socket heads having sockets therein for

fitting the nuts and bolt heads of varying sizes and different shapes and numbers of faces.

Although we have illustrated and described only a single form of the invention 70 we are aware of the fact that modifications can be made therein by any person skilled in the art without departing from the scope of the invention as expressed in the claims.

Therefore, we do not wish to be limited 75 to all the details of construction herein shown and described, but what we do claim is:—

1. As an article of manufacture, a ratchet wrench comprising a head, a handle secured thereto, said head being of cylindrical form and having a flat circular rack on its flat face consisting of a series of radial teeth projecting therefrom, a wrench socket having a rack fitting said teeth mounted on said head and rotatable thereon, said socket having an axial passage therethrough provided with a central recess, a stud in said passage having a head on its outer end movable axially in said recess, a spring acting normally to force said teeth together, and means at the inner end of the stud between the recess and handle for holding said socket on the head.

2. In a ratchet wrench, the combination of a head having a circular face provided with a series of ratchet teeth arranged in a circle on the face constituting a rack, said head having a recess extending inwardly and centrally from said face with a shoulder 100 at the bottom, a wrench socket placed in line with said head, and having a tooth engaging the rack on the adjacent face thereof, means detachably fixed in said head and bearing on said shoulder for preventing the removal of 105 the socket and yielding means for holding the socket in place to force the tooth into engagement with said rack.

3. In a ratchet wrench, the combination of a head having a handle projecting therefrom radially, said head being of cylindrical form and having a tooth on its end, a socket member having a circular rack on its end fitting against the end of said head and engaging the tooth thereon, said socket member having a socket for a nut or bolt head at its outer end, a headed stud therein and projecting from the face having a rack thereon, a spring for holding the socket member yieldingly on the stud, and means in said head for rigidly but detachably holding said stud thereon at its inner end.

4. In a wrench, the combination with a ratchet wrench head having a non-circular passage therein, of a rod having a similar 125 cross-section and provided with spring pressed means therein near its end for engaging a flat wall of said passage and holding the rod removably therein, and also provided with a circumferential groove there-

on, and a wire detachably mounted in said groove adapted to engage the external surface of said head when the rod is inserted therein.

5. In a ratchet wrench, the combination of a handle, a head located with its length at right angles to the axis of the handle and having a flat end provided with ratchet teeth thereon and having a central recess extending into it from the end, a wrench socket arranged in alignment with said head and having a circular series of teeth on its adjacent flat face constituting a circular rack
- 10 located in position to engage said teeth, of a central stud having a slotted head at one end and a reduced screw thread at the other screwing into the head, whereby it can be readily detached, said socket having a recess through which said stud extends, and a spring in said recess bearing on its bottom and on the under side of said head.
- 15 In testimony whereof we have hereunto affixed our signatures.

WILLIAM E. GIFFORD.
WILLIS R. SMITH.
